UNITED STATES PATENT OFFICE.

GEORGE H. BROWN, OF WILKINSBURG, PENNSYLVANIA.

BOTTLE-STOPPER.

1,247,497.

Specification of Letters Patent. Patented Nov. 20, 1917.

Application filed February 10, 1917. Serial No. 147,844.

To all whom it may concern:

Be it known that I, GEORGE H. BROWN, a citizen of the United States, residing at Wilkinsburg, in the county of Allegheny and State of Pennsylvania, have invented 5 certain new and useful Improvements in Bottle-Stoppers, of which the following is a specification.

This invention has relation to bottle stoppers, and has for an object to provide an improved stopper adapted for association with a specific form of bottle or other container; and providing means whereby the contents of the bottle or container may be 15 readily discharged when required, and whereby a closure for the container may be automatically formed by the stopper when the stopper is released.

Another object of the invention is to provide 20 a stopper having the above named characteristics whereby the same may be applied to a container for either liquid or powder, and whereby the substance may be dispensed from the container without waste, and without 25 permitting the entrance of deleterious substances into the container.

A still further object is to provide a stopper 30 of this character adapted to be applied to a form of bottle specifically adapted for association therewith, and whereby the stopper may be entirely removed from the bottle when the same is to be cleaned, and whereby the stopper may be again applied after the bottle has been resupplied.

35 In addition to the foregoing my invention comprehends improvements in the details of construction and arrangement of parts to be hereinafter more fully described and particularly set forth in the appended claims.

40 In the accompanying drawings in which similar and corresponding parts are designated by the same characters of reference throughout the several views in which they appear;

45 Figure 1, is a view in section of an improved bottle stopper and constructed after the manner of my invention.

Figs. 2 and 3 are horizontal sections taken 50 on the lines 2—2 and 3—3 respectively of the foregoing figure.

Fig. 4 is a section taken on the line 4—4 of Fig. 2, and

55 Fig. 5, is a sectional perspective illustrating the cap member and a portion of its interior.

With reference to the drawings, 10 indi-

cates a bottle having a constricted neck 11, and a bead 12 formed at the neck somewhat after the usual manner, except that in the present instance, the bead is extended radially to a greater extent than usual. The bead 12 is formed at opposite sides with notches 13, having their side walls disposed radially. The bead 12 is also provided at points intermediate the notches 13 with smaller notches 14 whose walls are parallel with the diametrical center of the bottle neck. Before proceeding further it is to be understood that I have illustrated as an example the provision of a bottle having a specially formed neck, nevertheless a metal container, or containers having other configurations may be employed, and similarly provided with a bead having notches, and constructed after the manner herein set forth.

My improved stopper comprises an inverted cap member having a cylindrical wall 16 and a top portion 17, which top portion is perforated centrally as at 18. The top member 16 is provided interiorly with opposed radially extending lugs 19 of a shape and size to correspond to the above mentioned notches 13 of the bottle. A perforated disk of cork or the like 20, is inserted within the cap member, and the lugs 19 should be disposed in spaced relation from the cover portion 17 of the cap member whereby when the cap member is applied to the neck of a bottle, the lugs 19 may be permitted to enter the notches 13 to a degree sufficient to permit the cap member to be subsequently rotated whereby to dispose the lugs 19 beneath the solid portion provided between the notches of the bead 12. 95 The cap member is furthermore rotated until reduced portions 21 formed on the upper surface of each lug 19 become coincident with the notches 14 of the bead 12, whereupon said reduced portions 21 may enter said notches thereby locking the cap member against accidental rotation.

A valve mechanism forms a part of the stopper and comprises an outer tubular member 22 which is inserted in the opening 18 of the cap member and is adapted to extend well into the neck of the bottle with its portion slightly projecting beyond the cap. An inner tubular member 23 of a diameter slightly less than that of the outer tubular member, is held concentrically in said outer tubular member and is provided

at its inner end with a radial flange 24, which is adapted to bear against the inner end of the outer tubular member. The opposite end of the inner tubular member ⁵ tends considerably beyond the projecting end of the outer tubular member and is externally threaded as indicated at 25. A flange 26 is internally threaded and applied to the threaded portion 25 of the inner tubular member 23, and a coil spring 27 is encircled about that portion of the inner tubular member which projects beyond the cap member and is interposed between the under side of the flange 26 and the outer surface ¹⁰ of the cap member being centralized by the engagement of the projecting end of the outer tubular member. The tubular member 23 is provided with an opening 28 at its inner end, and a flange 29 at its opposite end. ¹⁵ 20 In operation, the bottle or container, is inverted and the flange 26 pressed against the tension of the coil spring whereby to engage the flange against the outer projecting end of the outer projecting tubular member ²⁰ 22 whereupon the flange 24 of the inner end of the inner tubular member will become unseated from engagement with the adjacent end of the outer tubular member, whereby fluid is permitted to flow into the ²⁵ 30 opening 28, through the inner tubular member, and out of the same at its opposite end. By pressing the flange 26 lightly against the projecting end of the outer tubular member, sufficient air may be permitted to ³⁰ 35 enter the bottle to displace the contents which flow from the inner tubular member. It will be obvious that when pressure upon the spring is released, the flange 24 will immediately become seated to form a closure ³⁵ 40 for the container to prevent accidental ejection of its contents. It will also be obvious that when the bottle or container has been emptied, the stopper may be readily detached therefrom, the bottle refilled and the ⁴⁰ 45 stopper reapplied.

While I have illustrated and described my invention with some degree of particularity I realize that in practice various alterations may be made, and I therefore reserve the

right and privilege of changing the form of ⁵⁰ the details of construction or otherwise altering the arrangement of the correlated parts without departing from the spirit of the invention or the scope of the appended claims. ⁵⁵

Having thus described my invention, what I claim as new and desire to secure by Letters Patent is:

1. In combination, a bottle having a flanged neck with notches provided in the ⁶⁰ flange, and a plurality of smaller notches provided therein between the first mentioned notches, and a stopper in the form of a cap having inwardly projecting lugs ⁶⁵ adapted to enter the first mentioned notches when the cap is applied to the bottle, and whereby the cap may be rotated to dispose the notches and lugs out of alinement, and reduced lugs formed on the first mentioned notches adapted, when the cap is thus rotated to enter the smaller notches to lock the cap against rotation. ⁷⁰

2. A bottle stopper including a cap, a tubular member open at each end and secured in the cap, a second tubular member open at ⁷⁵ each end, movable in the first tubular member in spaced relation thereto, a valve on one end of the inner tubular member to close the adjacent end of the outer tubular member, a flange on the other end of the inner tubular ⁸⁰ member, and a coil spring encircling one end of the outer tubular member to engage the flange to retain the valve in closed position, said inner tubular member being movable to unseat the valve against tension of the spring ⁸⁵ and to seat the flange against the adjacent end of the outer tubular member, to insure passage of material through the inner tubular member and to permit replacement of air in the bottle through the outer tubular member, the flange being slightly unseated for ⁹⁰ this purpose. ⁹⁵

In testimony whereof I affix my signature in presence of two witnesses.

GEORGE H. BROWN.
